AUTOMATIC DRILLING MACHINE

James S. O'Callaghan, Marblehead, Mass.

Application April 27, 1942, Serial No. 440,745

6 Claims. (Cl. 77—26)

The invention relates to an improvement in automatic drilling machines, and one essentially adaptable for drilling a hole, or holes, in small objects.

The result sought for by the invention is a full automatic machine, or one which may easily be made full automatic.

The drilling machine constituting my invention shows the way in which the objective result above referred to may be secured, and consists of a combination which is characterized and attained by an association of elements, or parts, having such joint and co-operative action as to effect the objective end.

An example of a combination constituting my invention will now be described in the light of the drawings, and afterwards claims made therefor in the light of such description.

In the drawings:

Fig. 1 is a side elevation of the machine.

Fig. 2 is a front elevation of the top structure of the machine shown in Fig. 1.

Fig. 3 is a top plan of the machine.

Fig. 4 is a section on the line 4—4 of Fig. 1.

Fig. 5 is a section on the line 5—5 of Fig. 2.

Fig. 6 is a section on the line 6—6 of Fig. 1.

Fig. 7 is a cross section of certain of the working parts, later to be referred to, when in dormant position.

Fig. 8 shows especially the same elements as Fig. 7, excepting that the elements have been activated to assume an operative or working position.

Fig. 9 is a plan of the part, or object, drilled by the machine.

Fig. 10 is a cross section on the line 10—10 of Fig. 9.

Fig. 11 is a cross section of the mounting for the power drill hereinafter to be referred to.

Fig. 12 is a side elevation of various parts giving adjustability to the clamping head.

Fig. 13 is a plan of the clamping head shown in Fig. 12 disassociated from its adjustable parts; and

Fig. 14 is a plan of the clamping head with the adjustable parts applied to it.

Referring to the drawings—1 represents the frame of the machine having a top 2 with a vertical opening 3 through it at about the center of the table.

Located upon the top 2 are ways 4, 4, within which runs a slide 5 having a forked fore end 6. This forked fore end of the slide is adaptable to engage the object *a* to be drilled, when intro-

duced between the ways 4, 4, forward of the forked end of the slide, so that the object will be moved by the slide to a determinate centralized position over the opening in the table top where 5 the object is held clamped. The slide is moved by a lever 7 pivoted at 8 to the frame of the machine. This lever is under the control of a spring 10 and cam 11. The lever bears a cam roll 12 held in constant engagement with the 10 peripheral edge of the cam by the action of the spring 10. The cooperative action of these parts is such that the spring will act upon the lever to move the slide forward an amount sufficient to localize the object over the opening 15 in the table when so permitted by the cam, dependent upon the turned position thereof. As the cam turns another portion of its cam surface will act upon the lever to reverse the position of the slide. Thus a to and fro movement of the 20 slide is obtained. The cam 11 is arranged upon a cam shaft 14 journalled to turn in supports 15 fixed to the frame of the machine.

Fixed to the top 2 by bolting, or otherwise, is a piece 17. This piece spans the opening in the 25 top, leaving a passage 18 through the piece through which the object *a* to be drilled may pass. The head 19 of the piece overhanging the opening in the top forms a clamp member against which the object is held clamped, when positioned 30 over the opening in the top, by the operation of the slide.

Bolted or otherwise fastened to the under side of the top 2, in circumscribed relation to the opening in the top, is an annular head 20 from 35 which depends a tubular boss 21 with a vertical opening 22 through the head and boss. This opening is in axial alignment with the opening 3 in the top, but is of larger diameter than that of the opening in the top. Slidably contained 40 within the openings 3 and 22 is a sectional plunger comprising a section 24 slidable within the opening 3 in the top, and sections 25 and 26, respectively, slidable within the opening 22 in the top. Arranged upon the section 24 of the plunger and 45 interposed between the section 25 and the under side of the top 2, is a coiled spring 28. Interposed between, and connected, respectively, to the sections 25 and 26 of the plunger, is a coiled spring 29. Projecting centrally from the top free 50 end of the section 24 of the plunger is a pin 30 adaptable to enter the opening *b* through the center of the object *a* when the object is positioned over the opening in the top as aforesaid. The section 26 of the plunger protrudes beyond the boss 21 in which it slides, and the end of the

plunger section, so protruding, has bearing engagement against a lever 32. This lever is pivoted to the frame at 33. The lever bears upon its free end a cam roll 34 which engages the working surface of a cam 35 on the shaft 14. The parts are so co-ordinated that when the plunger is in its inactive position, as shown in Fig. 7, both springs 28 and 29 are under tension, the cam roll on the arm 32 being then yieldingly maintained by the springs in contact with the inactive portion of the cam. This action is initially obtained by the spring 28 which is then distorted to exert a force exceeding that obtained by the distortion of the spring 29. At this same time the pin borne by the section 24 of the plunger will lie substantially flush with the upper surface of the top 2 in position to enter the opening b in the object a when the plunger is activated to move vertically upward. The upward movement or advance of the plunger follows upward movement imparted to the plunger section 26 by the cam 25. As the plunger section 26 is moved upward by the cam, like movement is yieldingly applied to the plunger sections 24 and 25 through the spring 29 and the pin 30 on the free end of the section 24 will enter the opening b in the object a to be drilled, thereby assisting in centralizing its position. At substantially this same time, but following the centralizing of the object by the pin, the object will be held clamped between the end of the plunger section 24 and the head 19 on the top 2. The clamping of the object is in fact yieldingly effected owing to the presence of the spring 29 between the plunger sections 25 and 26. This spring will become highly contracted as the plunger is moved upwardly, and thus becomes the active force for yieldingly activating the plunger sections 24 and 25 for obtaining the centralizing and clamping of the object as aforesaid, thereby allowing for extremely quick action of the operating parts, and eliminating danger of breakage.

During the upward movement of the plunger for effecting the clamping operation the spring 28 will become highly compressed so that when the plunger is relieved of the activating force exerted by the cam 35 which lifts it, it will be returned to its normal position of rest by the spring 28. The spring 28 will then act to hold the spring 29 under a slight degree of contraction in order to maintain engagement of the intermediate parts with the cam and eliminate all lost motion, thus ensuring that all the parts of the plunger will become instantly active when the plunger section 26 is again raised by the operation of the cam.

During the time that the object is held clamped holes are drilled in it. For this purpose there is mounted upon the top 2 a set of power drills 40. These drills are preferably electrically driven. Each of these power drills has, affixed to its side, a housing 42. The housing may be secured to the body of the power drill by straps 43 connecting with the housing and passed around the body of the drill. Each of these housings is mounted upon a cradle 45 fixed to the top 2. The several power drills with affixed housings are set upon their cradles in an inclined position and with such placement that the ends of their drills 46 will normally lie contained within the clamping head 19, this head being provided with inclined openings 47 within which the ends of the drills are recessed. The inclination of these openings is such that when the drills are projected downwardly from the openings, and the drills rotated,

they will severally drill the requisite holes in the clamped object.

During the operation of the machine the power drills, kept active, rotating the drills 46 borne by them, are moved forward in their entirety for drilling the holes in the clamped object in the following manner.

Each of the power drills is slidably mounted upon its cradle through a dovetailed connection 49 between the top of the cradle and the bottom of the housing. The bottom of each housing is provided with a rack 50. Engaging this rack for the purpose of moving the housing and power drill to which it is attached, back and forth, is a pinion 52 fixed to the shaft 53 journaled to turn within the sides of the cradle and provided outside the cradle with a crank arm 54 by which it may be turned. These crank arms are collectively under the control of a disk 55 through links 56 pivotally connected, respectively, to the crank arms and to the disk. The disk 55 is provided with a sleeve 58 slidable upon the boss 21. Pivoted to the side of the sleeve is an arm 59. The opposite end of this arm is pivoted to a lever 60 at 61. This lever is pivotally secured at 62 to the side of the frame. The lever bears a cam roll 64 which is held in engagement with a cam 65, on the cam shaft 14, by means of a tension spring 66 interposed between the end of the lever and the top 2. This spring is in a state of tension, holding the cam roll 64 in constant engagement with the cam 65, and accordingly, through the connecting mechanism controlling the vertical position of the disk 55. When the disk is lowered, the power drills, through the intermediate connections which include the racks and pinions, will be projected forward for boring the holes in the clamped object. Following further turning of its controlling cam 65 the disk will be raised, retracting the power drills but leaving the ends of their drills 46 recessed within the head 19 of the clamping block.

After the drilling of the holes in the object a and its release from the parts holding it clamped, it is then subjected to the action of compressed air. The air enters by way of a pipe 68 which connects with branches 69, 70, and 71. These branches are so arranged as to direct the air passing through them through the passage 18 through the clamping block within which the drilled object is located. The air thus injected acts to blow the object along the table to a position where it is directed by a guide 72 to pass through an opening 73 in the table and thence through a chute 74 by which its passage is further directed. Compressed air which enters to pass through the pipe 68 enters the machine by way of a pipe 76 which connects with the inlet end of a valve 77 to the outer end of which pipe 68 is connected. The valve 77 is one of a common type in which its valve is a spring controlled valve normally held closed but which may be opened by a plunger 78 which, when depressed, will open the valve, but permitting its immediate closure when the pressure upon the plunger is relieved. The plunger is depressed by means of an arm 80 extending over it. One end of this arm is pivoted to a standard 81 on the frame of the machine and the other end of the arm is arranged to be struck by a cam roll 82 on a cam 83 on the cam shaft 14 as the cam 83 is rotated by the rotation of the shaft. As the cam is rotated its cam roll will strike the

arm 80 and momentarily depress the plunger, thereby providing for a momentary expulsion of compressed air, which is sufficient to expel the object from the table.

The cam shaft 14 is turned by means of an electric motor 84 through driven parts under the control of a foot treadle 85. To this end the electric motor is provided with a clutch 86 of common type normally inactive. The driven section of the clutch is provided with a shaft 87, and the clutch is rendered active for turning the shaft 87 by pressure of the engaging end 88 of the foot treadle against the end of this shaft. When the foot is removed from the treadle the clutch will be thrown out. Arranged upon the shaft 87 is a pulley 89 around which renders a belt 90. This belt is in driving connection and a pulley 91 on a shaft 92 suitably journalled to turn on the frame of the machine. The shaft is provided with a worm 93 which engages a gear 94 on the cam shaft 14. Thus the cam shaft is turned by the electric motor as long as the parts are rendered active by the depression of the foot treadle.

The various cams are disposed upon the cam shaft 14 in such order that they will severally perform their various functions in proper timed sequence to effect the resultant action attained by the machine, which includes the deposit of the article to be drilled in precise position to be clamped, the clamping of the object, the drilling of the object, and its ejection from its clamped position, the several operating parts being returned to their initial positions dependent upon the turned positions of the respective cams. All these operations take place during a single rotation of the cam shaft. In practice this rotation takes a little over a second, which means that each object is positioned, clamped, drilled, and ejected from the table, in a little over a second.

In order that the object, or article, to be drilled may be deposited over the opening in the table in the precise position it is to be clamped, the cam 11 is so cut that it will operate through the lever 7 to move the slide 5, which positions the object, with a relatively rapid movement at the beginning of its throw, but with slow movement as approach is made to the position where the object is to be left, so preventing momentum displacing the object, the object remaining in the precise position at which it is left by the slide.

If by chance the machine lacks an object to be clamped during a phase of its operation then, in such case, the plunger might be raised so far that the drills, then projected and operated, might engage the end of the plunger section 24 and disfigure it. This action, however, is prevented by a guard 95 borne by the plunger section 25. This guard in the normal working of the machine, when the plunger is raised, and the object held clamped, will not engage the under side of the top 2, but will stop just short of its under surface so as not to interfere with the proper clamping of the object. If there is no object to be clamped then this guard, on the upward stroke of the plunger, will engage the under side of the top and so prevent the section 24 of the plunger from being raised but a slight distance more than it would be raised if it were engaging an object for clamping it, thus ensuring that the drills when projected will not engage its top end.

The drills will strike the clamped object at points radially removed from the axial center of

the object, dependent upon the vertical adjusted position of the object with relation to the drills. Accordingly, in order that variation may be obtained in the location of the points where the drills first engage the clamped object away from its axial center, a vertically adjustable clamping head is provided against which the object is clamped by the operation of the plunger. This adjustable head has a set of adjustable pins 97 5 triangularly arranged passed through it. The head 19 then no longer provides the clamping member against which the object is held clamped by the operation of the plunger but rather its adjustable pins 97; the part 19 of the clamping block being raised so far that the pins may provide this clamping member. The vertically adjusted position of these pins provides variation in the distance away from the axial center of the object, when clamped, that the drills will 10 engage the top surface of the object. The pins 97 are borne by a plate 98 adjustably secured to the head 19 by adjusting screws 99 and the adjustment is secured by the introduction of one or more shims 100.

I claim:

1. In an automatic drilling machine for drilling holes in objects held clamped in successive order, the combination comprising, the frame of the machine with top having an opening in it, a clamping head in fixed connection to said top and bridging said opening in spaced relation thereto, a slide by which the objects to be drilled will be successively deposited over said opening beneath said clamping head, means for reciprocating said slide including a cam, a reciprocating plunger including a part movable through the opening in said top for clamping said objects when deposited as aforesaid and for releasing them as said plunger is reciprocated, means for reciprocating said plunger including a cam, a power drill arranged upon said top in position to drill said objects successively held clamped when said power drill is projected from a retracted position, means for projecting said power drill and 25 for effecting its return including a cam, means for removing said objects each from its clamped position after the drilling and release thereof including a cam, a common shaft bearing all of said cams, means for arranging the cams upon 30 said shaft whereby they will operate successively in proper timed sequence during a single rotation of said shaft, and means for turning said shaft.

2. In an automatic drilling machine for drilling holes in objects held clamped in successive order, the combination comprising, the frame of the machine with top having an opening in it, a clamping head in fixed connection to said top and bridging said opening in spaced relation thereto, a slide by which the objects to be drilled will be successively deposited over said opening beneath said clamping head, means for reciprocating said slide including a cam, a reciprocating plunger including a part movable through the opening in said top for clamping said objects when deposited as aforesaid and for releasing them as said plunger is reciprocated, means for reciprocating said plunger including a cam, a power drill arranged upon said top in position to drill said objects successively held clamped when said power drill is projected from a retracted position, means for projecting said power drill and for effecting its return including a cam, a common shaft bearing all of said cams, means for arranging the cams upon said shaft 35 whereby they will operate successively in proper timed sequence during a single rotation of said shaft, and means for turning said shaft.

timed sequence during a single rotation of said shaft, and means for turning said shaft.

3. In a drilling machine for objects held clamped in successive order, the combination comprising, a frame having a top with opening in it, a clamping head affixed to said top and arranged to bridge said opening, means whereby said objects will be successively deposited over said opening beneath said clamping head, a reciprocable plunger operable through said opening in the top for clamping said objects against said head when deposited as aforesaid, a boss affixed to said top within which said plunger is reciprocable, means for reciprocating said plunger, a plurality of power drills mounted upon said top and set in position to simultaneously drill said objects in the successive order of their clamping upon the projection of said drills from a retracted position, means for slidably mounting said power drills whereby they will be projected and retracted, mechanism for controlling the projected or retracted position of said power drills including for each of said power drills an oscillatory crank arm, means for oscillating said crank arms including a reciprocating disk having pivoted link connections with said arms, a sleeve bearing said disk slideable upon said boss, and means for reciprocating said disk through said sleeve including a rotary cam.

4. In a drilling machine for objects held clamped in successive order, the combination comprising, a frame having a top with opening in it, a clamping head affixed to said top and arranged to bridge said opening, means whereby said objects will be successively deposited over said opening beneath said clamping head, a reciprocable plunger operable through said opening in the top for clamping said objects against said head when deposited as aforesaid, said plunger comprising a plurality of sections, one a top section adaptable to pass through the opening in said top, the others, an intermediate section and a bottom section each of larger diameter than the opening through said top, a spring interposed between and connected, respectively, to said intermediate and bottom sections, a spring interposed between said intermediate section and said top, means affixed to said top within which said plunger is reciprocable, and means for reciprocating said plunger whereby it will intermittently engage and assist in the clamping of said objects as they are successively deposited over the opening in the top and be returned to an inactive position.

said objects as they are successively deposited over the opening in the top and be returned to an inactive position.

5. In a drilling machine for objects held clamped in successive order, the combination comprising, a frame having a top with opening in it, a clamping head affixed to said top and arranged to bridge said opening, means whereby said objects will be successively deposited over said opening beneath said clamping head, a reciprocable plunger operable through said opening in the top for clamping said objects against said head when deposited as aforesaid, said plunger comprising a plurality of sections, one a top section adaptable to pass through the opening in said top, the others, an intermediate section and a bottom section each of larger diameter than the opening through said top, a spring interposed between and connected, respectively, to said intermediate and bottom sections, a spring interposed between said intermediate section and said top, a guard borne by said intermediate section constructed and arranged to engage said top when said top section of the plunger rises unduly through said opening in the top during the projection of the plunger for lack of an object to be clamped, means affixed to said top within which said plunger is reciprocable, and means for reciprocating said plunger whereby it will intermittently engage and assist in the clamping of said objects as they are successively deposited over the opening in the top and be returned to an inactive position.

6. In a drilling machine for objects held clamped in successive order, the combination comprising, a frame having a top with opening in it, a clamping head affixed to said top and arranged to bridge said opening, said clamping head having a plurality of adjustable pins passed through it into the space above said opening, means for adjustably fixing said pins, means for depositing the objects to be drilled in successive order over said opening and beneath said pins of the clamping head, and a reciprocable plunger operable through the opening in said top and engaging each object deposited as aforesaid whereby the object so deposited will be held clamped between said pins and the end of said plunger.
